DESIGN FOR A BOTTLE CASE

Hulet L. Livesay, Milwaukee, Wis., assignor to Western Metal Specialty Company, Milwaukee,
Wis., a corporation of Wisconsin

Application December 2, 1944, Serial No. 116,674

Term of patent 14 years

(Cl. D58—4)

To all whom it may concern:

Be it known, that I, Hulet L. Livesay, a citizen of the United States, residing at Milwaukee, in the county of Milwaukee and State of Wisconsin, have invented a new, original, and ornamental Design for Bottle Case, of which the following is a specification, reference being had to the accompanying drawing, forming part thereof.

The dominant features of my design reside in the portions shown in full lines in the drawing.

I claim:

The ornamental design for a bottle case, as shown and described.

HULET L. LIVESAY.
